UNITED STATES PATENT OFFICE.

ETHAN I. DODDS, OF AVALON, PENNSYLVANIA, ASSIGNOR TO THE PRESSED STEEL CAR COMPANY, OF PITTSBURG, PENNSYLVANIA, A CORPORATION OF NEW JERSEY.

CAR-FRAME.

SPECIFICATION forming part of Letters Patent No. 784,665, dated March 14, 1905.

Application filed February 11, 1904. Serial No. 193,060.

To all whom it may concern:

Be it known that I, ETHAN I. DODDS, of Avalon, Allegheny county, Pennsylvania, have invented a new and useful Car-Frame, of which 5 the following is a full, clear, and exact description, reference being had to the accompanying drawings, forming part of this specification, in which—

Figure 1 is a vertical section through the 10 center sill of a car, showing a body-bolster in elevation and showing the flanged tension member which is applied to the bolster and extends through the center sill. Fig. 2 is a 15 top plan view of Fig. 1, partly in section, on the line II II. Fig. 3 is a side elevation of the center sill, showing the body-bolster in section. The figures on Sheet 2 show a modification of the invention. Fig. 4 is a vertical cross-section through the center sill, showing 20 the tension member also in vertical section. Fig. 5 is a view of Fig. 4, partly in plan and partly in horizontal section. Fig. 6 is a vertical section on the line VI VI of Fig. 5. Fig. 25 7 is a detail view showing a tension member which can be employed when the bolster is composed of parallel flanged beams. Fig. 8 is a vertical section through a bolster constructed with the tension member of Fig. 7, the center sill being shown in elevation. Fig. 30 9 is a plan view of a modified construction. Fig. 10 is a side elevation thereof in section through the center sill. Fig. 11 shows in perspective the parts of the tension member illustrated in Figs. 9 and 10. Fig. 12 is a vertical 35 section on the line XII XII of Fig. 9.

In the figures on Sheet 1 of the drawings I show the center sill of a car constituted of parallel channel-beams 22. The body-bolster, which extends at right angles to the center 40 sill, is composed of members 33, which abut at the inner ends against the center sill and are connected thereto by suitable connecting-angles 4. The members 33 are preferably constituted of sections of I-beams divided 45 with a bias cut longitudinally through the web, so as to make each member of tapering form, having the original flanges 66 of the I-beam along its bottom edge and having the upper or cut edge unflanged. The bolster

members 33 are connected by a tension member 55, constituted by angle-bars which are riveted to the upper edge of the bolster members and extend along the same from end to end of the bolster through holes *c* cut for that purpose in the centersill. The tension member 55 connects the parts of the bolster firmly together, and when so constructed lateral and longitudinal thrusts are well resisted. The members of the bolster are also preferably connected by a bottom tie-plate 6, which extends across the center sill.

In the figures on the second sheet of the drawings the continuous tension member does not extend through but over the center sill. Thus in Figs. 4, 5, and 6 the bolster members 65 extend to the plane of the top of the center sill, whereas in Fig. 1 the center sill extends to a higher level. The bolster has on each side of the center sill two bolster members 3', each constituted as above with reference to 70 Fig. 1, set at an angle to each other and connected by parts 77 at the outer ends and bottom, so as to produce a bolster tapering from the middle to the ends. The connecting tension member is a plate 5', which is fitted upon 75 the top of the bolster members and center sill, is unflanged where it crosses the members of the center sill, but along the bolster members has marginal flanges *d* which are riveted to 80 said members.

In Fig. 7 I show a tension member 55 of a form which may be used when the members of the bolster are parallel, as in Fig. 8. This tension member is preferably made of a channel-beam from which the flanges are removed 85 at the center. In Fig. 8 I show the bolster members made of I-beams, and in Figs. 4, 5, and 6 they are made of channels.

In Figs. 9, 10, 11, and 12 I show a modified construction wherein the bolster is constituted 90 by a single bolster member 33 on each side of the center sill, made as shown in Figs. 1, 2, and 3 and fixed to the sill at the inner end by angle connections 4. The sill is made of parallel channel members with inwardly-directed 95 flanges. The tension member consists of two pieces 55, each adapted to extend along the bolster members and across the center sill,

each having a vertical flange *ee* riveted to the upper edge of the bolster member and cut away where it crosses the sill and having a flat top portion tapering from the middle toward the ends. These tension-member pieces are preferably made by dividing a channel-beam longitudinally through the web with angled cuts.

Within the scope of my invention as stated 10 in the claims the parts of the device may be modified in various ways, since

What I claim is—

1. In combination with a center sill, bolster members on opposite sides of the sill and a 15 flanged tension member uniting the bolster members across the center sill, said bolster members having integral flanges along their lower edges; substantially as described.

2. In combination with a center sill, bolster 20 members on opposite sides of the sill and a tension member extending along the bolster members across the center sill, said bolster members having integral flanges along their lower edges, and the tension member being 25 flanged and applied to the upper unflanged edge of the bolster members; substantially as described.

3. In combination with a center sill, bolster members on opposite sides of the sill and a flanged tension member extending along the 30 unflanged edges of the bolster members and across the center sill, said bolster members being constituted in sections of flanged beams divided longitudinally through the web with bias cuts; substantially as described. 35

4. In combination with a center sill, bolster members having unflanged upper edges and abutting against opposite sides of the sill, and a flanged tension member extending along 40 said bolster members and across the sill, said tension-member flanges being omitted above the sill; substantially as described.

5. In combination with a center sill, a plurality of bolster members on opposite sides of the sill, and a flanged tension member uniting 45 the bolster members, said tension member being unflanged where it crosses the center sill; substantially as described.

In testimony whereof I have hereunto set my hand.

ETHAN I. DODDS.
